Patented June 10, 1862, City of New York May 19, 1862.

Gillmore L. Kelty

Dec. 1604

Gibbons L. Kelly - New York, N.Y.
Letters Patent No. 1604 dated June 14, 1862,

The schedule referred to in these Letters Patent and making part of the same,

To all whom it may concern:

Be it known that I, Gibbons L. Kelly, of the City and State of New York, have invented, or produced a new and original ornamental design for the top part of Tassels, and I do hereby declare the following to be a full, clear and exact description of the nature of the said design, reference being had to the annexed photographic representation of a tassel with my ornamental design applied thereto.

The skirt or fringe of the tassel is of any usual character; my ornamental design consists of an acorn shaped mould at or near the top part of the tassel at the point where the cord attaches to the same.

The acorn shape is covered and to increase the beauty of the finish a net work of silk or other material surrounds the cup shaped base of the acorn to give an appearance approaching that of the natural acorn.

What I claim and desire to secure by Letters Patent is the design of the ornamental acorn shaped top to the tassel as represented.

In witness whereof I have hereunto set my signature this 19th day of May, 1862.

Witnesses,

Henry Frank Gossells. }
Tho. J. Harold,

Gibbons L. Kelly
